A. M. EICHORN

RUBBER HEEL TIP

Filed July 18, 1923

UNITED STATES PATENT OFFICE.

ARTHUR M. EICHORN, OF NEW YORK, N. Y., ASSIGNOR TO EVERNU RUBBER HEEL CORPORATION, OF NEW YORK, N. Y., A CORPORATION OF DELAWARE.

RUBBER HEEL TIP.

Application filed July 18, 1923. Serial No. 652,252.

To all whom it may concern:

Be it known that I, ARTHUR M. EICHORN, a citizen of the United States, residing at New York city, borough of the Bronx, in the county of Bronx and State of New York, have invented certain new and useful Improvements in Rubber Heel Tips, of which the following is a specification.

This invention relates to rubber or cushion heels for shoes and has particular reference to that type of heel tips in which there are provided two main parts,—one to be secured permanently to the heel, and the other to be detachably connected thereto for such purposes as renewal or adjustment to compensate for wear.

Among the objects of the invention is to provide a rubber heel tip molded or otherwise formed in a peculiar manner, mainly of solid resilient rubber, but having suitable reinforcing and stiffening means embedded therein.

Another object of the invention is to provide a renewable or interchangeable rubber heel tip made with holes therein for the insertion of a novel type of tread members so designed as to serve as anti-slipping means and also as anchorage means to hold the tip in normal wearing position.

A still further object of the invention is to provide an improved type of keeper or locking means for securing the renewable or interchangeable tip removably to the fixed portion of the heel.

A still further object of the invention is to provide heel tip devices in which for each heel there is a removable tip or point portion of a composition best suited for individual use according either to his peculiar inclinations or the occasion for which the devices are worn. In other words, for the ordinary use of a pedestrian a soft resilient cushion is desirable, but for other uses such as dancing a hard tip is required, and by my improvement I provide tips of various qualities or natures and interchange them according to the occasion.

In the practice of this invention the separate parts of the construction may be made in various designs or modifications, some of which are illustrated, and I wish it to be understood that the illustrations are to be interpreted as suggestive of the broader aspects of the invention, rather than as limitations of particular construction. Illus-

trations, for example, of alternative forms indicate that the kinds of material employed may vary somewhat, and accordingly certain parts may be of different specific design, but the general spirit of the invention remains without substantial variation except as may be permitted by the scope of the claims and the state of the art.

Of the drawings, in which similar or related parts are referred to by similar reference characters,

Figure 1 is a vertical longitudinal section on the line 1—1 of Fig. 2.

Fig. 2 is a bottom plan view.

Fig. 3 is a detail perspective view of the reinforcement plate for the base portion.

Figs. 4 and 5 are alternative forms of keepers.

Fig. 4^a is an edge view of the keeper of Fig. 4.

Figs. 6 and 7 are alternative forms of reinforcement means for the removable or interchangeable tip member.

Fig. 8 is a further modification of the reinforcement means for the tip, having a suggestion of integral locking means.

Fig. 9 is a detail view of a preferred form of anchor pin for the tread plugs used in connection with the renewable tip.

Fig. 10 is a modification of the tip of harder composition than for use as shown in Fig. 1.

Referring now more specifically to the drawings I show my improvement as comprising a relatively permanent attachment members or base 10 made largely of rubber for cushioning purposes, and within it is molded a reinforcement plate 11. This plate is provided with a plurality of holes 12 for attachment screws or nails 13 and through which the base may be secured readily and reliably to the leather portion 14 of the heel. The plate 11 is formed with a plurality of larger holes or openings 15 through which the main rubber body of the base may pass for strengthening the connection between the metal and rubber parts. Also along the central portion of the plate 11 is formed a channel 16, as by swaging downward a portion of the plate at 17. The ends of this channel are practically open, and located in the channel is a keeper formed either as from wire stock as at 18 in Figs. 4 and 4^a, or from sheet metal as at 18' in Figs. 1 and 5. The keeper 18 is shown

provided with a plurality of shouldered holes 19, one near its rear end and the other toward the other end, while at its forward end it is provided with finger pieces 20 which when pressed toward each other cause the opening or widening of the holes 19. Portions of the keeper 18 are bent or offset upward as shown in Fig. 4, and the looped inner end 21 is preferably more flexible than the main portions. Fig. 5 shows a slidable keeper 18' having tapered or keyhole slots 19' formed by slotting the metal from which the keeper is formed. At the front end of the channel portion 17 of the plate is struck upward a tongue 23 serving to co-operate with the slot 22 to limit the forward movement of the keeper. The offset portion 21 or the runners 21' formed by striking up edge portions of the slidable keeper 18' serve to compel the keeper in either form to bear against the bottom of the channel. The eye portion 20' of the keeper 18' may be grasped by any suitable tool or instrument such as a hook as shown at 24 for drawing it forward or pushing it rearward into locking position.

The part of the heel tip that receives the direct impact against the pavement and hence must sustain practically all the wear may have any suitable form in plan view and be made to have any desired thickness or depth in proportion to the tread portion of the base 10 already described. In its preferred form this renewable tip portion is shown at 25 as circular or disk like in form, and hence for convenience will be referred to throughout this description as the disk. For walking and usual shock sustaining purposes the disk is made preferably of softer and more resilient stock and a little thicker than the fixed tread member. Being circular in form the rear or point portion of the disk conforms substantially to the usual shape of shoe heel as indicated in Fig. 2. The fixed portion of the base 10 is recessed at 26 to accommodate the front portion of the disk. Either or both of the base and disk parts may be provided with non-slip or friction tread members such as plugs or inserts 27 and 27', preferably molded of suitable composition of rubber and anti-slip material. As indicated the disk is made to accommodate four of the plugs 27 while the front or breast tread portion of the base is fitted with two of the plugs 27', one adjacent to each corner thereof and preferably in axial alignment with the corner holes 12 of the plate 11. The periphery of the disk at its bottom surface is preferably beaded at 28 to add not only to its appearance but especially to its wearing qualities, and at its center the disk is provided with a cavity 29 for the application of a trade-mark or other identification means.

The disk, irrespective of its precise form in plan or the extent to which it covers the base 10, is preferably molded or otherwise formed with a plurality of holes 30 formed directly vertically therethrough, each having smooth and preferably cylindrical sides, but having an offset or shoulder 31, the larger end of the hole being toward the bottom surface of the disk. The plugs 27 are fitted into and preferably cemented in these holes, and each plug is formed with a shoulder or offset 32 bearing directly against the shoulder 31. Likewise each of the plugs 27' may be provided with a shoulder 32' to bear against a correspondingly formed shoulder or offset in the bottom of its hole or seat 33. The bottom or tread surface or end of each plug is preferably rounded or crowned and so projects slightly beyond the main surface of the part into which it is fitted.

Each plug 27 is molded or otherwise formed to include an anchorage member in the nature of a double headed pin 34. This pin preferably has a relatively flat head 35 and square shoulder at its upper exposed end which projects far enough beyond the upper end of the plug to be received through one of the keyholes 19' in the keeper 18'. The lower end 36 of each pin is shown preferably as flared and extended closely contiguous to the shoulder portion 32 of the plug body. This flanged end 36 of the pin 34 may assume any desired form but by reaching toward the edge of the shoulder 32 it makes strong anchorage co-operation with the shoulder portion of the hole surrounding it.

While the tread or major portion of the disk, except as just described in connection with the plugs, is of relatively soft cushion material, I provide a stiffening or reinforcement means for the upper or anchorage portion thereof, which may take the form shown best in Fig. 6 as comprising a wire member 37 bent into a circle and also into as many similar loops 38 as there are holes 30, one loop 38 being embedded in the shoulder portion 31 of each of said holes. Hence the reinforced shoulder portion of each plug 27 will bear substantially snugly against the reinforced portion of the disk.

In connecting the disk to the base 10 the keeper 18' is simply drawn forward and the disk is then put directly into place in the seat 26, the heads 35 of the pins 34 coming into similarly arranged pits or seats in the adjacent bottom surface of the base 10, after passing through the larger end portions of the keyhole slots 19' of the keeper. Since the keeper is held urged downward by reason of the runners 21', the heads 35 will be received directly into the smaller ends of the slots 19' when the keeper is pushed rearward into its nested position. When, how-

ever, the keeper is drawn forward till stopped by the tongue 23 striking against the end of the slot 22 the larger ends of the key-holes will permit the heads 35 to pass freely 5 outward, permitting the disk to be turned around its vertical axis and returned to original position so as to present a fresh wearing surface at the point of the heel, where most of the wear is received. In this 10 manner each disk will serve about four times as long as an ordinary heel tip of similar stock and will enable the wearer to present always a substantially flat heel, not only for the sake of the appearance of the shoes, but 15 more particularly for comfort in walking.

As shown in Fig. 2 it will be noted that the front tread portion of the base 10 is formed to comprise two rearwardly projecting points 39, which when of rubber are naturally somewhat resilient, and to stiffen this 20 part of the construction the anchor plate 11 is formed with a pair of upwardly extending spurs 40. Each of these spurs is provided with a transverse hole 41 through 25 which the molten rubber projects during the molding operation, thus providing a very effective interlock between the rubber and these parts of the plate.

The plugs 27' so far as their operation is 30 concerned are preferably similar to the plugs 27, and moreover they serve to close the openings through which the corner nails or fasteners 13 are driven through the base plate 11.

At 42 I show a reinforcement ring as an 35 alternative form for the ring 37, the same being made of sheet metal stamped into an annular form and having holes 43 formed therein for the passage of the smaller ends 40 of the plugs 27. The edges of these holes 43 correspond in position and function to the loops 38 above described.

In Fig. 8 I show a further modification of 45 reinforcement ring 42' which instead of being provided with holes 43 has pins 43' struck upward therefrom for co-operation with either keeper the same as the heads of the pins 34. In this adaption of the device 50 the plugs, if used with the disk, may take the form of the plugs 27' above described.

As premised above, for dancing purposes any ordinary rubber heel tip is objectionable for obvious reasons, and so to meet the demand for shoes with suitable heels for this 55 purpose I provide tips 25' as shown in Fig. 10, the same being made of any suitable material harder than the tips 25 above described and intended primarily for pedestrianism. The tips 25' are provided with plugs 60 27' fitted into holes formed through the tips and having anchorage pins 34 with heads 35 made uniformly with those already described so that either set of tips may be removed 65 and the other put in place readily according to the occasion. The composition of the

tips 25' may be harder than the other tread member at the breast portion of the base 10. It will thus be appreciated that my invention lends itself directly to the use of any desired hardness or quality of the tips that are 70 not only interchangeable as to sets, but adjustable around their own axes as a result of wear.

I claim:

1. A rubber heel tip comprising, in combination, a base portion, means to secure said base portion permanently to a heel, a separable portion, and means to secure the separable portion to the base portion, the latter mentioned securing means comprising a 75 headed cushion plug in one of said portions and a member carried by the other of said portions and movable transversely of said headed plug and having an opening into which the headed plug is received, the opening being narrow enough to closely embrace the neck portion of the headed plug when moved to locking position.

2. The herein described rubber tip for 80 shoe heels, the same comprising a base, means to secure the base to the heel as a permanent fixture, a separable tread member, and means to attach the tread member 85 removably and interchangeably to the base, said attaching means comprising rigid 90 headed plugs carried by the tread member and whose heads project upward therefrom, and means movable horizontally along the base member and having close interlocking 95 embracing co-operation with the heads of 100 the headed plugs.

3. In a heel attachment, the combination 105 with a base, of a cushion member adjustable with respect to the base and having openings formed therethrough from its tread surface, anchor members for the cushion member fitted in said openings, and means carried movably by the base and co-operating selectively with certain of the anchor members to lock the cushion member in one 110 position and with different anchor members when the cushion member is adjusted as aforesaid.

4. In a heel attachment, a cushion member 115 having a plurality of openings formed therethrough from its tread surface, an anchor member fitted in each of said openings, the cushion member being symmetrical with respect to its vertical center and adjustable therearound and the anchor 120 members being symmetrically disposed around said center, and a keeper co-operating selectively with certain of said anchor members to secure the cushion member in place and with other anchor members when the cushion member is adjusted as aforesaid.

5. In a heel attachment, the combination 125 of a relatively rigid base member having a central longitudinal channel and having on 130

- opposite sides of the channel a plurality of seats, a keeper movable within said channel and having a plurality of spaced openings therein, a tread member for detachable and interchangeable co-operation with the base member, and means co-operating with said keeper for locking the tread member of the base member, said last mentioned means including two sets of rigid headed members 10 projecting upward from the tread member, one set of said headed members projecting into the seats aforesaid and the other set projecting into the channel and through the openings in the keeper and interlocked in 15 said openings as a result of the movement of the keeper transversely of the headed members co-operating therewith.
6. A device as set forth in claim 5 in which the tread member is circular and the headed members are arranged concentrically therewith, the tread member being adjustable around its center to bring either set of the headed members into co-operation with the keeper while the other set 20 will project into the seats, the locking means serving after each adjustment to fix the tread member from rotation.
7. In a heel attachment of the character set forth, a cushion member, rigid fasteners 25 for securing the cushion member in operative position, said cushion member having openings from its tread surface through which said fasteners are passed, and molded plugs fitted into and closing said openings, the fasteners including parts molded in the 30 plugs.
8. In a heel attachment, the combination with a rigid part of a heel structure, of a cushion member having openings therethrough from its bottom tread surface, means to secure the tread member to the 35 rigid structure aforesaid, said means including rigid fasteners passed upward through said openings into the rigid heel structure.
- and plugs of non-slip composition fitted 45 into and closing said openings and in which the rigid fasteners are embedded.
9. The herein described plug for attaching heel tips comprising a solid body having vertical sides and one end thereof being 50 larger than the other, and a rigid fastening pin embedded in the body and projecting from the smaller end thereof, the larger and smaller portions of the plug being 55 united in an offset shoulder portion and the fastening pin having its end within the body extended radially outward contiguous to said shoulder.
10. The herein described tip for shoe heels comprising a disk shaped body of resilient material having a plurality of holes formed upward therethrough, each hole being larger at one end than the other and having an offset shoulder between the two end portions, an annular reinforcing member 60 of wire embedded within the body and concentric therewith and having individual coils surrounding each of said openings and lying contiguous to the shoulder thereof, and a plurality of plug members fitted in 65 and filling said holes and bearing adjacent to the reinforcing member, said plug members serving as anchorage means.
11. In a heel attachment, the combination with a base, of a cushion member for the 70 base having an opening formed therein, a frictional anchor member fitted in said opening, said anchor member having a head, and a movable keeper secured to said base and having an opening therein for a 75 slidable detachable engagement with the anchor member behind said head, thereby securing said cushion member detachably to said base.

In testimony whereof I affix my signature.

ARTHUR M. EICHORN.
